UNITED STATES PATENT OFFICE.

WILLIAM E. STEVENS, OF NEW HAVEN, CONNECTICUT, ASSIGNOR TO SARGENT & COMPANY, OF NEW HAVEN, CONNECTICUT, A CORPORATION OF CONNECTICUT.

DESIGN FOR A CASKET-TRIMMING.

SPECIFICATION forming part of Design No. 35,876, dated April 15, 1902.

Application filed December 13, 1901. Serial No. 85,856. Term of patent 14 years.

To all whom it may concern:

Be it known that I, WILLIAM E. STEVENS, of the city and county of New Haven, State of Connecticut, have invented a new Design for a Casket-Trimming, of which the following is a full, clear, and exact description, when taken in connection with the accompanying drawings and letters of reference marked thereon, which drawings constitute a part of this specification, and in which—

Figure 1 represents a front view, and Fig. 2 an edge view, of a casket-trimming embodying my design.

My invention relates to a design for a casket-trimming.

The design consists in the configuration and ornamentation, as hereinafter described, and shown in the accompanying drawings.

The design is herein shown applied to a plain casket-plate; but it will be understood that it is equally applicable to handle-socket plates.

The trimming, which is rectangular in its general form, comprises a field A, having a plane surface and an ornamental border B, of substantially an architectural design, representing what is known as a "false arcade." The lower portion of the border consists of a straight molding C, extending entirely across

the plate, the molding C being supported by 30 a band D, having a series of ornamented medallions E, with depressions F between the several medallions. On both ends of the trimming the border represents columns G, 35 surmounting the molding C and supporting in turn across the top three ogee canopies H, carrying a flat molding I. At the points where the canopies H meet the border resembles corbels J, while superimposed on the vertices of the canopies it takes the form of ornamented finials K. Within the canopies is a representation of a feathering L of general trefoil design, while between the canopies are circular medallions M, corresponding to those in the base of the molding D. 45

Having now described my invention, what I claim, and desire to secure by Letters Patent, is—

The design for a casket-trimming, as herein shown and described. 50

In witness whereof I have hereunto set my hand, in the presence of two subscribing witnesses, this 11th day of December, 1901.

WM. E. STEVENS.
